UNITED STATES PATENT OFFICE.

FRANK H. BLACKINTON, OF CHESTER DEPOT, VERMONT.

TOOL-POST.

1,246,226.

Specification of Letters Patent. Patented Nov. 13, 1917.

Application filed January 18, 1917. Serial No. 143,173.

To all whom it may concern:

Be it known that I, FRANK H. BLACKINTON, a citizen of the United States, residing at Chester Depot, in the county of Windsor 5 and State of Vermont, have invented certain new and useful Improvements in Tool-Posts; and I do declare the following to be a full, clear, and exact description of the invention, such as will enable others skilled in 10 the art to which it appertains to make and use the same.

My invention has for its object to provide a simply constructed yet highly efficient tool post for lathes and the like, so mounted as 15 to permit the tool to be tilted downwardly and upwardly and adjustable longitudinally of the lathe carriage as well as vertically.

With the foregoing general object in view, the invention resides in certain novel features of construction and unique combinations of parts to be hereinafter fully described and claimed, the descriptive matter being supplemented by the accompanying drawings which constitute a part of this application and in which:

Figure 1 is a side elevation of the invention;

Fig. 2 is a top plan view thereof;

Fig. 3 is a vertical section on the plane of 30 the line 3—3 of Fig. 2;

Fig. 4 is a vertical section at right angles to Fig. 3 cut substantially on the plane of the line 4—4 of Fig. 2;

Fig. 5 is a perspective view of the rocker;

Figs. 6 and 7 are similar views respectively of the inner and outer wedges.

In the drawings above briefly described the numeral 1 has reference to a suitable base adapted to be mounted on a lathe carriage for movement transversely of the line of travel of said carriage, said base having a horizontal bore 2 formed transversely therethrough and opening through its upper side. The bore 2 receives therein a rocker 3 in the form of a sleeve split along its upper side at 4 and having its edges spaced apart and disposed in downwardly converging relation, the lower side of the sleeve being decreased in thickness as indicated at 5 so as to permit said sleeve to readily expand and contract to respectively hold it against or permit rocking movement in the bore 2.

A semi-cylindrical anchor member or 55 wedge 6 is disposed within the rocker 3 and the reduced lower end of a tool post 7 is

swiveled to said wedge, said post having the usual vertical slot 8 to receive the lathe tool 9 and a screw 10 for clamping said tool in position. A V-shaped wedge 11 is slideable vertically on the tool post 7 and is received between the downwardly converging edges 4 of the rocker 3 so that as this wedge is forced downwardly by tightening of the screw 10, it and the wedge 6 will coöperate 60 in expanding the rocker 3 to bind the latter frictionally against the wall of the bore 2. The upper side of the wedge 11 is formed with a boss 12 upon which a tool rest 13 in the form of an annular nut is threaded by 70 means of rather coarse threads. By this provision, the tool 9 may be adjusted vertically to the required extent.

By the construction above described, it 75 will be obvious that loosening of the screw 10 will permit the rocker 3 to turn in the bore 2 so that the active end of the tool 9 may be lowered or raised in respect to the work, thus insuring that it be presented at the proper angle for accomplishing the best results. This arrangement of parts also allows the tool post to be adjusted longitudinally of the rocker 3 and thus permits the tool to operate at the extreme left hand end of the work. Also, as above stated, the tool 85 is rendered vertically adjustable by the rest 13. The improved device is particularly advantageous for holding boring tools but it is also adapted for numerous other purposes, and regardless of its use will be extremely 90 efficient.

On account of the advantages above set forth, the construction shown and described constitutes the preferred embodiment of the improved tool post but it is to be understood that within the scope of the invention as claimed, numerous changes may be made.

I claim:

1. The combination with a support having a horizontally extending bore opening 100 through its upper side, of an expansible rocker mounted in said bore, a tool post rising from said rocker, means coacting with said post for clamping a tool in place, and means for automatically expanding the 105 rocker when said clamping means is tightened.

2. The combination with a support having a horizontally extending bore opening 110 through its upper side, of an expansible rocker mounted in said bore, a tool post rising from said rocker and adjustable along

- the same, means coacting with said post for clamping a tool in place, and means for automatically expanding the rocker when said clamping means is tightened.
5. The combination with a support having a horizontally extending bore opening through its upper side, of an expansible rocker mounted in said bore, a tool post rising from said rocker, means coacting with 10 said post for clamping a tool in place, and means mounted on said post for automatically expanding said rocker when the clamping means is tightened.
4. The combination with a support having a horizontally extending bore opening through its upper side, of an expansible rocker mounted in said bore, a tool post rising from said rocker, means coacting with 15 said post for clamping a tool in place, and a wedge mounted on the post for automatically expanding said rocker when said clamping means is tightened.
5. The combination with a support having a horizontally extending bore opening 20 through its upper side, of an expansible rocker mounted in said bore, a tool post rising from said rocker, means coacting with said post for clamping the tool in place, and a pair of wedges disposed respectively 25 on the interior and exterior of said rocker and mounted on the tool post for automatically expanding the rocker when the clamping 30 means is tightened.

6. The combination with a support having a horizontal bore opening through its upper side, of a split sleeve received in said bore and having its split disposed upwardly, 35 an anchor member disposed in said sleeve, a tool post rising from said anchor member and having a transverse slot to receive a 40 tool, a tool rest to receive said tool thereon, said rest having a wedge extending into said split of the sleeve, and a clamping screw threaded downwardly through the upper 45 end of said post and into the slot thereof.

7. The combination with a support having a horizontal bore opening through its upper side, of a split sleeve received in said bore and having its split disposed upwardly, 50 a wedge in said sleeve, a tool post extending into said sleeve through the split thereof and swiveled to said wedge, said post having a transverse slot to receive a tool, a tool rest slidable on said post and including a wedge extending into the split of said sleeve, 55 and a set screw threaded downwardly through the upper end of the post for clamping the tool in place.

In testimony whereof I have hereunto set my hand in the presence of two subscribing 60 witnesses.

FRANK H. BLACKINTON.
